(57) **CLAIM**

I claim the ornamental design for a golf ball shaped urn, substantially as shown and described.

DESCRIPTION

FIG. 1 is a front elevation view of the golf ball shaped urn. FIG. 2 is a top plan view of the golf ball shaped urn, the bottom of the golf ball shaped urn is a mirror image of the top; and,

FIG. 3 is a front exploded view of the golf ball shaped urn. The broken line portions of the drawings are for illustrative purposes only and form no part of the claimed design.

1 Claim, 3 Drawing Sheets*Fig. 1*
